UNITED STATES PATENT OFFICE.

ANDERS G. ANDERSON, OF WORCESTER, MASSACHUSETTS, ASSIGNOR TO EDMUND CONVERSE, OF WORCESTER, MASSACHUSETTS.

BICYCLE.

SPECIFICATION forming part of Letters Patent No. 692,811, dated February 11, 1902.

Application filed November 20, 1899. Serial No. 737,721. (No model.)

To all whom it may concern:

Be it known that I, ANDERS G. ANDERSON, a citizen of the United States, residing at Worcester, in the county of Worcester and 5 Commonwealth of Massachusetts, have invented a new and useful Improvement in Bicycles, of which the following is a specification, accompanied by drawings forming a part of the same, containing a full, clear, and exact description of my invention.

My invention relates to the construction of the tubular frames of bicycles, and particularly to the coupling by which the tubular frame known as the "rear braces," "seat-post tube," and the "upper strut" are joined together; and it consists in certain novel features of construction by which the said coupling may be made of sheet metal and its resistance to the various strains to which it is 20 subjected largely increased, as hereinafter described, and pointed out in the annexed claims.

In the accompanying drawings, Figure 1 represents a side elevation of my improved 25 coupling with portions of the framework connected thereto represented in broken lines.

Fig. 2 is a top view of my improved coupling with the inner dovetailed tube removed. Fig. 3 is a sectional view on line A A, Fig. 2, with 30 the inserted dovetailed tube shown in full. Fig. 4 is a sectional view on line B B, Fig. 2; and Fig. 5 is a top view of the crescent-shaped tie-piece by which the coupling is reinforced, with the parts attached thereto shown in sectional view.

Similar letters refer to similar parts in the different figures.

Referring to the drawings, lines A, B, and C denote, respectively, the upper strut, the 40 central post or diagonal tube, and one of the rear braces of a bicycle-frame, which are shown as joined together by one of my improved couplings D, which is formed from a suitably-shaped sheet-metal blank by means of a drop- 45 press in the usual and well-known manner in making bicycle-fittings of this class, forming a three-pronged sheet-metal coupling, with each of the prongs D', D², and D³ reduced in diameter, forming nipples D⁴ to receive the ends of the tubular members A B C 50 of the bicycle-frame, which butt against the

shoulders D⁵ and form a "flush joint." The prong D', which receives the upper strut A, and the divergent prongs D² D³, which receive the rear braces, are united by and are 55 integral with a tubular center D⁶, in which is inserted the reduced end E' of a shortsheet-metal tube E, formed by rolling up a piece of sheet metal having dovetailed edges, which are engaged to form a joint, so that the dovetails E² upon one edge will interlock the dovetails E³ upon the opposite edge and unite the edges to form a tube, which will resist an interior strain tending to expand the tube. The end of the dovetailed tube E projects below 60 the tubular center D of the coupling and forms a nipple to receive the central post or diagonal tube B of the frame and receives the bicycle seat-post, which in many bicycles are held in position by an expanding device applied to the interior of the seat-post tube. It is therefore desirable that the tube E be able to resist interior pressure, which would expand the tube; and I accomplish this result 65 by interlocking the dovetailed edges of the 70 blank to prevent them from being forced apart.

In forming the coupling D, I make the two divergent prongs D² D³, where they join the central tubular section D⁶, so that the inner 80 edges F² of the abutting sides F F' will be flush with the opening through the central tubular section D⁶ in order to bring them in contact with the reduced end E' of the tube E. Each of the abutting sides F F' is notched at F³ to 85 receive a crescent-shaped tie-piece G, which is likewise notched at G' to slip over and inclose the abutting sides F F'. The notch in the tie-piece G locks the two abutting sides F F' together and resists any strain tending to separate the divergent prongs D² D³, and the notch in the edges of the sides F F' holds the crescent-shaped tie-piece in position with its concave edge G² in contact with the reduced end E' of the tube E. When the crescent-shaped 95 tie-piece G has been placed in position, the reduced end E' of the tube E is inserted in the tubular central portion D⁶ of the coupling, and all the surfaces in contact with the reduced end E' are brazed together, and the 100 completed coupling is then introduced to the frame by sliding the ends of the connected

tubular members A, B, and C over the nipples D⁴, to which they are brazed. Any tendency to expand the coupling, whether by an expanding device such as is commonly used for maintaining the seat-post in position or by any of the strains incident to the use of the bicycle will be resisted both by the dovetailed joint of the inserted tube E and also by the abutting sides F F' of the divergent prongs D² D³, and the crescent-shaped tie-piece, which is brazed to the inner tube E, serves to lock the abutting sides F F' together.

What I claim as my invention, and desire to secure by Letters Patent, is—

1. As an article of manufacture the within-described coupling for bicycle-frames comprising a central portion to receive a seat-post tube and having a prong D' and divergent prongs D² and D³ with their adjacent sides F and F' abutting and provided with notched edges and a notched tie-piece engaging the

notched edges of said abutting sides, substantially as described.

2. In a bicycle the combination in a coupling of a central tubular portion to receive a seat-post tube, a prong D' and divergent prongs D², D³, their adjacent sides F, F' abutting and provided with notched edges, a notched crescent-shaped tie-piece engaging the notched edges of said abutting sides, and a tube E having interlocked dovetailed edges inserted in said central portion and abutting the concave edge of said tie-piece, substantially as described.

In testimony whereof I have signed my name to this specification, in presence of two subscribing witnesses, this 16th day of October, 1899.

ANDERS G. ANDERSON.
